US00D732034S

(12) **United States Design Patent**
Chen et al.

(10) **Patent No.:** US D732,034 S
(45) **Date of Patent:** ** Jun. 16, 2015

(54) **SCANNER**

(71) Applicant: **AVISION INC.**, Hsinchu (TW)

(72) Inventors: **Chi-Yao Chen**, Nanhuang Township, Miaoli County (TW); **Jui Cheng Liu**, Nantou (TW); **Chao Yu Peng**, Hsinchu (TW)

(73) Assignee: **Avision Inc.** (TW)

(**) Term: **14 Years**

(21) Appl. No.: **29/489,171**

(22) Filed: **Apr. 28, 2014**

(30) **Foreign Application Priority Data**

Mar. 10, 2014 (TW) 103301330

(51) **LOC (10) Cl.** **14-02**

(52) **U.S. Cl.**

USPC **D14/420**

(58) **Field of Classification Search**

Primary Examiner — Susan Moon Lee

(57) **CLAIM**

The ornamental design for a scanner, as shown and described.

DESCRIPTION

FIG. 1 is a left perspective view of a scanner showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
